[57] CLAIM

The ornamental design for a ground fault circuit interrupter, as shown and described.

DESCRIPTION

FIG. 1 is a reduced front perspective view of a ground fault circuit interrupter showing our new design;

FIG. 2 is a top plan view thereof;

FIG. 3 is a front elevational view thereof;

FIG. 4 is a right side elevational view thereof, the left side elevational view being a mirror image;

FIG. 5 is a rear elevational view thereof;

FIG. 6 is a bottom plan view thereof.

FIG. 1

FIG. 2

FIG. 3

FIG. 4
